Inventor
Hector Mitchel Marion
Per Frank J. O'Leary, Attorney.

UNITED STATES PATENT OFFICE.

HECTOR MITCHEL MORISON, OF NEWBURY, ENGLAND.

CHICK BROODER.

Application filed March 13, 1924. Serial No. 698,979.

To all whom it may concern:

Be it known that I, HECTOR MITCHEL MORISON, of Sonimor Poultry Farm, Leckhampstead, Newbury, in the county of Berkshire, England, a subject of the King of Great Britain and Ireland, have invented a new and Improved Chick Brooder (for which I have filed application in Great Britain No. 21,723, filed the 28th August, 1923), of which the following is a specification.

This invention relates to a new or improved chickbrooder for poultry, whereby better control of the source of heat can be obtained together with proper ventilation and prevention of the massing or huddling of the chicks under the brooder.

In carrying out the invention, I incorporate in the brooder a mass of porous material in the shape of curtains, coverlets and so forth, to which heat is imparted by means of a heating element or elements which is or are preferably a pipe or pipes through which hot water flows and which may be formed in various designs and so disposed as may be found most advantageous or efficient for heating. In its preferred form the brooder may comprise a roof, as it were, formed by the heating element, from which the curtains described above depend. They are preferably strung upon rods so as to be easily removable, the rods being supported by the piping or by the framing used to connect the convolutions of the piping together. The edges of the curtains are slit or snipped to form loose tongues and allow freedom of movement to the chicks. The heating element may be provided with a cover which may have dependent sides which are then slit or snipped similar to the curtains, and the whole brooder may be suspended so as to be adjustable for height above the ground or floor.

The accompanying drawings show the preferred form of construction.

Fig. 1 is a perspective view of the whole brooder assembled together but with the top cover cut away to show the arrangement of the piping and curtains beneath.

Fig. 2 is a detail showing more clearly a single curtain and its supporting rod.

Figs. 3 and 4 show different shapes of the heating element.

Referring to Fig. 1 of the drawings, the heating element consists of a flat coil of pipes 1 which are connected where necessary

by elbow bends 2 and are supported in the same plane by upper and lower strips 3 secured together by bolts 4. Hot water enters and leaves the heating coil through flexible supply and exit pipes 5 and 6. Downwards from the pipes depend curtains 7 which as shown in Fig. 2 are threaded upon rods 8 which project from each end of the curtain, the projecting portions resting upon the strips 3. Thus any particular curtain can be removed at will. The curtains are of course of different lengths to suit the spaces between the successive coils of piping, and they may be of varying depths, for instance, they may decrease in depth progressively from the outside to the inner space under the heating element. They are made of flexible material and are slit or snipped as shown in Fig. 2 so as to form loose tongues 9 to allow freedom of movement for the chicks.

The brooder is provided with a cover 10 spread across the heating element and this cover may have dependent sides 11 which in that case are slit or snipped so as to form loose tongues 12 similar to the tongues 9.

The whole brooder may be suspended by cords or cables 13 by which its height above the floor or ground can be regulated or by means of which it can be entirely removed for cleaning purposes.

The heating element may have various shapes as may be found most convenient or efficacious under the particular circumstances. Figs. 3 and 4 show two variations from the shape shown in Fig. 1.

When the heating coil is of the form shown in Fig. 3, a continuous bar may be used which supports a strip, as shown in Fig. 2, the rods being of such thickness that the slitted fabric and rod will be maintained by the coil, and in Fig. 4 the rods 8 and curtains 9 will rest upon adjacent pipes depending from the rectangular coil.

It will be appreciated that the degree of heat of the brooder can be regulated with great ease by means of the removable curtains, which is of great importance in a variable climate. The device also adapts itself with great facility as a cold brooder, the mass of warm material affording snug quarters for the chicks even without the additional heating possible by means of the piping.

I claim—

A brooder for poultry, comprising in com-

bination a coil of pipes constituting a heating element, flexible supply and exit pipes to and from said heating element, a framework adapted to engage said heating element, dependent curtains of flexible material mounted on rods carried by said framework, said curtains being slit to form loose tongues, a coverlet for the brooder of flexible porous

material said coverlet having dependent sides also slit to form loose tongues and 10 means for suspending the brooder at an adjustable height, substantially as described.

In witness whereof I have signed this specification.

HECTOR MITCHEL MORISON.
